Fig. 4.

UNITED STATES PATENT OFFICE.

ENOCH LARSON, OF ELDORA, IOWA.

DISPLAY RACK.

Application filed March 9, 1927. Serial No. 173,925.

The object of my invention is to provide a display rack for shoes of simple, durable and inexpensive construction.

It is my purpose to provide a display rack 5 for shoes of a knock-down type, which can be assembled or taken down and packed in a small space for storage or transportation without the use of bolts, nails, or other independent fastening devices, which might be 10 likely to become lost or misplaced.

It is more particularly my object to provide such a display rack in which the end members may be connected by means of shoe supporting elements, which not only 15 rigidly connect and support the end members but provide means for supporting shoes in position inclined downwardly and forwardly, so as to afford the most satisfactory display of the shoes.

20 With these and other objects in view, my invention consists in the construction, arrangement and combination of the various parts of my display rack, whereby the objects contemplated are attained, as herein- 25 after more fully set forth, pointed out in my claims, and illustrated in the accompanying drawings, in which:

Figure 1 shows an end elevation of a display rack embodying my invention.

30 Figure 2 is a front elevation of the same.

Figure 3 is a perspective view of one of the shoe supporting racks with the central portion thereof broken away and omitted; and.

35 Figure 4 is a detail, sectional view taken on the line 4—4 of Figure 1.

My improved display rack for shoes may be made in as many units as may be desired.

A unit has two end members. The end 40 members comprise an upright indicated in the accompanying drawings by the reference numeral 10 and may be of wood or any suitable material. Spaced laterally from each end member 10 on opposite sides 45 thereof are supporting members 11, which are inclined from the horizontal from their lower ends toward the adjacent member 10 at their upper ends, as illustrated in Figure 1.

50 The supporting members 11 and the end member 10 at each end of the complete unit

are connected by cross bars 12 arranged in vertical, parallel series on opposite sides of the end member 10. The cross members 12 are secured to the members 11 and 10 by 55 means of bolts 14 as shown in Figure 1.

The bars 12 are inclined from the member 10 downwardly and outwardly to the members 11 as shown in Figure 1. At their inner ends, where they are secured to the 60 member 10, the ends are beveled as indicated at 16 in Figure 1, for giving better rigidity to the display rack.

The lower cross bars 12 are connected with the member 10 by braces 18 bolted to 65 these lower cross bars between their ends as at 20 and to the member 10 as at 22.

On the top of each cross bar 12 between the ends thereof is a short bar 24.

The upright 10 extends upwardly above 70 the upper cross bars 12 and has in its upper end a notch 26.

Where a single unit is employed, it is provided with two of the end members, such as that shown in Figure 1. 75

Where it is desired to provide two or more units, then at the extreme ends of the completed display rack, I use end members, such as that shown in Figure 1, and intermediate of the respective units, I use a supporting intermediate member, which is similar to that shown in Figure 1 with the following modifications:

This intermediate supporting member has 80 an upright 10^a similar to the upright 10. It has on its opposite sides, sets of members 12^a and 12^b similar to the members 12 and secured to the upright 10^a in the same manner that the members 12 are secured to the upright 10. 85

At the outer ends of the members 12^a and 12^b are members 11^a and 11^b similar to the members 11 shown in Figure 1.

I have indicated the end member shown in Figure 1 by the reference character A 90 and the intermediate support shown in Figure 2 by the indicating character B. The members B are similar to the members A, except however, that the members B have two sets of cross bars 12^a and 12^b instead of 100 one set 12 and have two sets of members 11^a and 11^b instead of the members 11. 95

The members B may also have four of the braces 18^a instead of two of them as shown in Figure 1.

I will now describe the manner in which 5 a unit is built up.

It will be understood that a unit may have two members A if desired, but I will describe my display rack as though it were made of two units with members A at the 10 extreme ends and one intermediate member B.

In such a structure the members A and B are connected by shoe racks or shelves, such as that indicated generally at C in Figure 15 3.

Each shoe rack has generally speaking the form of a rectangular frame, comprising the longitudinal frame members 28, and 30, which are connected near their ends by 20 the connecting bars or frame members 32 secured to the undersides of the members 28 and 30. The member 28 is preferably thicker from top to bottom than the member 30 for reasons, which will be hereafter 25 explained.

I provide a clip at each end of each member 28 and 30. These clips indicated generally at D are made in the form of angle bars, each having a substantially horizontal flange 34 secured to the underside of the member 28 or 30 as the case may be, and projecting between that member and the frame member 32.

At the outer end of each portion 34, the 35 clip D has a downwardly projecting flange or ear 36 flush with the end of the member 28 or 30.

In assembling the units of the display rack, the shoe racks or shelves C are placed 40 in position with the ends of the members 28 and 30 resting upon the bars 12 and 12^a or 12^b. The bars 12 and 12^a or 12^b are received between the members 32 and the flanges 36 as clearly shown in Figure 4.

45 The parts are assembled so that the members 24 fit snugly between the members 28 and 30, as shown for instance in Figure 1.

The members 10 and 10^a may be connected by cross brace wires, cables or the like 50 38, which are preferably connected with the members 10 and 10^a by means of hooks 40 and rings 42, but may be connected in any suitable way.

It is thus seen that I have provided a display rack having a number of substantial 55 advantages.

It is preferably made mainly of wood but may be made of any suitable material adapted for the purpose. If made of metal, it 60 may be painted or colored to represent wood.

I have provided a display rack for shoes, which may be assembled in as many units as may be desired.

If only one unit is preferred, I use two 65 of the end members A and a suitable num-

ber of shoe racks or shelves C. If two units are desired, I use two end members A, one intermediate member B, and as many shoe racks C as are required.

It will be seen that several units may be 70 assembled if desired.

The jobber or dealer need keep on hand only three kinds of units, to-wit, the units A, B and C, together with the wire or cable braces 38.

In installing the display rack in a store, as many of the units may be built up as may be desired.

When the units are assembled, they are 80 strong and rigid and they afford means for displaying shoes in a most advantageous way.

On account of the slant or inclination of the members 12, 12^a and 12^b, it will be seen that the shoes are displayed so as to afford 85 a satisfactory inspection. They are tilted downwardly and forwardly somewhat for more convenient examination.

The members 28 are somewhat thicker 90 than the members 30 to afford ample strength for supporting the heavier weight of the shoes. The members 30 are slightly thinner than the members 28 because they do not need to support so much weight.

The making the members 28 thicker than 95 the members 30 also contributes to the convenient placing of the shoe as indicated at 44 in its downwardly and forwardly tilted position, since the member 28 rests under the instep of the shoe, while the member 30 rests under the forward part of the shoe.

The members of each unit are securely 100 locked together and the different units are rigidly connected.

The rack can be taken down readily and 105 packed into a very small space for transportation and storage by releasing the tie braces 38 and lifting off the shoe racks C, whereupon the members A and B can be laid down flat and the members C piled 110 thereon.

I have thus provided a rack which can be conveniently packed or shipped in knock-down form, occupying a minimum of space. The rack can, however, be put together 115 without the use of nails, bolts, screws or other loose parts and when assembled will be strong and rigid.

The shoes are held in a very advantageous 120 position for examination by the customer.

The shoe racks are so placed as to make the placing of the shoes thereon convenient and easy.

The rack has a slightly appearance.

Bars 46 may be placed in the notches 26 to afford means for supporting advertising cards, signs and so on. This explains the reason for extending the members 10 and 10^a above the upper bars 12.

Heretofore it has been difficult to advan- 130

tageously display shoes in a store, where they can be fully inspected by the customer.

My rack affords a neat, convenient and efficient means for displaying a large number of shoes for the customer's inspection. When not in use, it can be taken down and stored.

Various materials may be used in making up my improved rack, and some changes may 10 be made in the details of its construction and arrangement without departing from the real spirit and purpose of my invention, and it is my intention to cover by my claims, any modified forms of structure or use of 15 mechanical equivalents, which may be reasonably included within their scope.

I claim as my invention:

1. In a shoe display rack, end members each comprising central uprights, cross bars 20 secured thereto and inclined downwardly therefrom on opposite sides thereof, supporting members fixed to the outer ends of said cross bars and inclined from their upper ends outwardly and downwardly, brace 25 members connecting said central, upright members with certain of the cross bars, shoe racks each comprising spaced longitudinal frame members connected near their ends by bars secured to their undersides, and downwardly projecting engaging members on the shoe racks spaced outwardly from said last-described bars, said racks being placed on said end members with the bars of the end 30

members received between the cross bars and downwardly extending members of the respective shoe racks. 35

2. In a shoe display rack, end members each comprising an upright, bars fixed to the upright in pairs extending downwardly and away therefrom in opposite directions, 40 uprights spaced from said central member on opposite sides thereof and fixed to the ends of the respective series of bars, an intermediate supporting member similar to the end member, except that it has double 45 sets of the bars, and upright supports at the other ends thereof, bars being arranged on opposite sides of the central upright of said intermediate member, and shoe racks for connecting the end members with the intermediate member, comprising spaced longitudinal members connected by transverse end members secured to the underside of the longitudinal members near their ends, and downwardly projecting members on the 50 longitudinal members spaced from the cross members of said shoe racks, the longitudinal members of said shoe racks resting on the respective bars of the end members, and intermediate members, with the bars of said 55 end members and intermediate members received between the respective cross members and downwardly projecting members of the shoe racks.

Des Moines, Iowa, March 3, 1927.
ENOCH LARSON.
